(57)

CLAIM

The ornamental design for an interlocking artificial grass tile, as shown and described.

DESCRIPTION

FIG. 1 is a front perspective view of an interlocking artificial grass tile showing our new design;

FIG. 2 is a rear perspective view thereof;

FIG. 3 is a front elevational view thereof;

FIG. 4 is a rear elevational view thereof; and,

FIG. 5 is a rear elevational view of the interlocking artificial grass tile in a position of use.

The broken lines in FIG. 5 depict environmental subject matter that forms no part of the claimed design
